Primary Examiner — Ian Simmons*Assistant Examiner* — Rhea Shields(74) *Attorney, Agent, or Firm* — Chun-Ming Shih; HDLS IPR Services(57) **CLAIM**

The ornamental design for a paper box having slope, as shown and described.

DESCRIPTION

FIG. 1 is a perspective view of a paper box having slope showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an exploded view showing the paper box having slope.

The broken lines shown represent unclaimed subject matter and form no part of the claimed design.
